UNITED STATES PATENT OFFICE.

CARL M. BERNEGAU, OF HOBOKEN, NEW JERSEY, ASSIGNOR TO THE KEUFFEL & ESSER COMPANY, OF HOBOKEN, NEW JERSEY, A CORPORATION OF NEW JERSEY.

CALCULATING-MACHINE.

No. 882,614.

Specification of Letters Patent. Patented March 24, 1908.

Application filed November 27, 1906. Serial No. 345,398.

To all whom it may concern:

Be it known that I, CARL M. BERNEGAU, a citizen of the United States, residing at Hoboken, in the county of Hudson and State 5 of New Jersey, have invented certain new and useful Improvements in Calculating-Machines, of which the following is a specification.

This invention relates to a certain class of 10 calculating machines, such, for instance, as that forming the subject matter of United States patent to Alexander Rechnitzer, No. 809,075, dated January 2, 1906, and that forming the subject matter of French patent 15 to Thomas, numbered 138,912 and dated Sept. 29, 1880, in which there are a series of drums or barrels actuated simultaneously by hand or power, through the medium of a shaft having a bevel gear engaging with a 20 similar gear on the shaft of each drum. In the patented machines each drum has a series of nine teeth of graduated length so that a pinion slidable on a parallel shaft may be located so as to engage with any number 25 of the teeth of the drum during each revolution thereof to govern the extent of rotation of the shaft carrying the pinion. The slide- 30 able pinion is attached to a button projecting downward from the top or face of the machine through a graduated slot, the position of the button and consequently of the slide- 35 able pinion being indicated, on the top of the machine by a pointer on the button coöperating with the numbers (from 0 to 9) on the side of the graduated slot in said top. Thus, if a button indicator points to say the 40 numeral 7 at the sides of one of the graduated slots, the slide- 45 able pinion will be in position to be engaged with seven of the teeth of the drum below it, and the shaft carrying the slide- 50 able pinion will be rotated the distance of seven teeth during each complete rotation of the drum.

The shaft upon which the slide- 55 able pinion is mounted is connected with and actuates the calculating mechanism so that the extent of operation of the calculating mechanism is governed by the position of the button in the graduated slot in the top of the machine, 60 there being a drum, slide- 65 able gear, graduated slot, and button for each digit of the number being used in the operation of the machine.

In the practical operation of machines of 65 this class, the slide- 70 able button arrangement has been found to be objectionable to some

extent. In setting up a number by means of these slides there is a liability to over-run, or pass by, the proper number on the side of the graduated slot causing at times considerable annoyance and loss of time in correctly setting the slide. At present it is particularly necessary to examine the position of each slide after it has been set in order to be sure that no accidental displacement has occurred. There is also a liability 60 of the sleeve of the operator catching on such a slideable button without his knowledge in moving the hand and arm over the top of the machine, and thus unintentionally setting up a number where none is desired to 65 be enumerated, or of disarranging a button already set and thus changing an item already enumerated; in either case, the result being an operation upon a wrong number and a wrong result. It is essential that all 70 liability to such error be obviated in order that the machine is reliable in result.

It is the object of the present invention to remedy the defects now existing in machines of the class described and with this 75 object in view I provide such machines with keyboards and keys instead of the graduated slots and slide- 80 able buttons.

This invention consists therefore in the improved construction, arrangement and 85 combination of parts hereinafter fully described and afterwards specifically pointed out in the claims.

In order to enable others skilled in the art to make and use the invention, I have illustrated it in the accompanying drawings in 90 which

Figure 1 is a plan view illustrating the application of my invention to a machine of the Rechnitzer class, only two denominational 95 series of keys being shown, and the irrelevant parts being omitted; Fig. 2 is a front elevation of the parts shown in Fig. 1 back of the vertical plane on the line 2-2 in Fig. 1, some parts in front of this plane being also 100 shown. Fig. 3 is a plan view of the same parts below the plane of the line 3-3 in Fig. 2. Fig. 4 is a vertical section on the plane of the line 4-4 in Fig. 1 on an enlarged scale, some parts being shown in elevation and 105 some being broken away to show concealed parts, Fig. 5 is a perspective view of the mechanism for moving the slide- 110 able gear above referred to, and Fig. 6 is a detail plan showing the connection between the pinion

shaft of my improved key and the numeral wheels of the patented mechanism.

Referring to the drawings, 10 indicates the top of the stationary portion of the machine 5 in which at a convenient place there is a slot through which projects the starting lever of the machine. This starting lever is the means employed to control the operations of addition, subtraction, multiplication and 10 division as is fully explained in the United States patent to Rechnitzer above referred to. The machine is also provided, as is explained in that patent, with a sliding carriage which carries the calculating mechanism. These parts form no part of my invention 15 and are therefore not illustrated in the drawings.

A shaft 11 (see Fig. 1) actuated from any suitable source of power is supported in suitable bearings 12, 12, in the frame of the machine. It is provided with a number of beveled gears 13, 13, one gear corresponding with each denominational series of keys on the key board and each gear being rigidly secured to the shaft 11.

A series of drums 14, 14, (see Fig. 4) are mounted on shafts 15, 15, at proper intervals along the machine, one drum being provided for each denominational series of keys 30 on the key board. Each of said shafts is provided with a beveled gear 16 which is adapted to engage with the corresponding gears 13, 13, on the shaft 11 whereby the drums 14, 14, are continuously rotated so 35 long as the shaft is actuated. These drums 14, 14, are each provided with nine teeth, 17, 17, of progressively increasing length forming in effect mutilated gears (most clearly shown in Fig. 5) one tooth corresponding on 40 said drum to each of the digits in each denominational series. The shaft 11 is adapted to be continuously rotated when once started until its necessary revolution is completed.

45 Mounted in convenient proximity to the mutilated gears, are numeral wheel shafts 18, 18, (see Figs. 3 and 6) one for each drum, 14, supported to rotate in suitable bearings 19 and 20 formed in the framework of the machine. Each shaft is made preferably of 50 prismatic form along that portion of its length opposite the mutilated gear and between these bearings 19 and 20 and carries a 55 slideable pinion 22 (best seen in Fig. 5) which is apertured in polygonal outline in cross section to fit over the prismatic section of the shaft and is adapted to slide freely thereon, but which by reason of the prismatic form of the shaft and the corresponding form of the aperture 60 in the pinion must, when rotated, communicate the motion of the pinion to the shaft.

Each one of the slideable pinions is provided with means whereby it may be slid along the shaft comprising a hub 23 (Fig. 65 5) adapted loosely to embrace the shaft

and having an annular flange 24 adapted together with the lateral surface of the pinion 22 to engage with a carrier 25 by the movement of which the pinion is slid. The carrier 25 is moved in one direction under the 70 tension of a spring 26 secured to it and to a collar or post 27 fixed to a rod 28 suitably mounted in the frame of the machine and along which the carrier is adapted to move. In the other direction, the carrier is positively moved back to its original position 75 by mechanism hereinafter described. The carrier comprises a guiding sleeve 29 adapted to encircle the rod 28 so that the carrier may be moved freely on said rod without danger of lateral displacement or vibration; a lower projecting member 30 adapted to engage with the flange 24 or the pinion 22, as the case may be, and an upper projecting member 31 adapted to engage with the key stems 80 hereinafter described.

Mounted at the top 10 of the machine is a key board comprising a bank of keys 50, 50, (see Fig. 4) arranged in denominational series, each series consisting of keys having 90 finger tips 51 numbered from 1 to 9 respectively, and arranged in staggered positions in order to economize space across the top of the machine. Each key is provided with a depending stem 52 adapted to be reciprocated in a guide tube 53 and provided with a retracting spring 54 arranged between the finger tip and the top of the guiding tube. Each key is also provided at its lower extremity with a foot 55, having toes 100 56, 56, (see Fig. 5) turned inwardly and forming between them and the bottom of the foot a passage way 57 adapted to permit of the passage of the upper member 31 of the carrier 25. The foot is also provided externally with grooves 58, 58, (see Fig. 5) which serve as guide ways to coöperate with a stationary guide 59 provided with guide ribs 60, and which guide is secured to the top 10 of the machine. By this means when 110 the key is depressed its foot is caused to move without lateral displacement and in a proper vertical plane.

The upper projecting member 31 of the carrier 25 is provided with lateral fingers 32 115 (Figs. 4 and 5) adapted to engage with the toes 56, 56, of the key stems. It is also apertured at 33 to permit of the passage of a U-shaped latch bar 40 (Fig. 4) which is pivoted at each end to the extremities of 120 the guide 59 and which passes through all of the passage ways 57 of the key stems of the entire denominational series. The latch bar is provided with a shoulder 41 which is adapted to engage the upper member 31 of 125 the carrier 25 to hold the latter in its initial position, and constitutes a lock or latch for that purpose. A spring 42 (see Figs. 4 and 5) is secured to the latch bar 40 and to the frame of the machine and serves to retract 130

this bar to position after its depression, which occurs through contact with the foot of the particular key which has been depressed in the enumeration of an item upon the key board.

The mechanism by means of which the carriers and slidable pinions are restored to their initial positions (see Fig. 3) comprises a restoring bar 61 suitably interrupted or grooved at 62, 62, so as not to interfere with other stationary parts of the mechanism and which is adapted to be manually or otherwise moved across the machine to sweep back or positively move to their initial positions all of the carriers which have been moved out of such positions in the enumeration of the items set up on the key board.

The means employed preferably to actuate the restoring bar is best shown in Figs. 2 and 3. In the illustrations, the bar 61 is shown provided with suitable lugs 610, 610, internally threaded to engage with threaded shafts 63, 63, suitably mounted in bearings in the frame of the machine and on the extremities of which shafts are rigidly secured pinions 64, 64, adapted to mesh with a spur gear 65 mounted on a shaft 66 provided with a projecting handle 67. This spur gear has a hollow hub 68 inside of which is arranged a coiled spring 69; one end of which is secured to the shaft 66 and the other end of which is secured to a pin 70 fastened in the frame of the machine. This spring serves to retract to position the spur gear after it has been rotated by means of the handle.

In order to simplify the description, I have shown but two of the denominational series of keys in the key board. These are, however sufficient to illustrate the construction and mode of operation of my invention. It will of course be understood that by increasing the number of denominational series I correspondingly increase the capacity of the machine, the other instrumentalities being made accordingly.

The numeral wheels of the Rechnitzer machine are mounted beneath the sliding carriage (not shown). They comprise wheels 70 mounted on a shaft 71 which also carries gear wheels 72 connected by trains of gearing 73 with the shaft 18 (best shown in Fig. 6) and it will be understood that the purpose of my invention is, by the depression of a key on the key board, to move the slidable pinion of its denominational series to such a position that the shaft 11, when rotated, shall, through the medium of the drum 14 and its gearing, give a proper number of turns to the shaft 18 to actuate the numeral wheels to a proper degree.

The operation of the mechanism above described is as follows: When it is desired to set up an item on the key board, the keys representing that item are depressed, one key in each denominational series corresponding

to the digits of the item to be enumerated. Take, for instance, the denominational series of keys shown in end elevation in Fig. 4 and suppose the key carrying the digit "1" and which projects furthest above the top 10 of the machine is the one selected. The depression of the key tip 51 moves downwardly the key stem and its foot 55. This foot is thus brought into contact with the upper surface of the latch bar 40 and depressing the latter removes its lug 41 from contact with the upper member 31 of the carrier 25. This carrier, under the influence of the energy stored in the spring 26, moves toward the left as shown in Fig. 4, the aperture 33 permitting the carrier to pass along the latch bar 40 until its upper member 31 comes into contact with the side of the foot 55 of the key which has been depressed, when, of course, it stops. This movement also brings the fingers 32 into position above the toes 56 of the foot 55 and prevents any upward movement of the key stem when the operator ceases to press downward upon the key tip.

The carrier, as has been seen, has been brought to rest against the side of the depressed key stem and the parts are so adjusted that the slidable pinion 22 which has been moved with the carrier 25 will be brought opposite the longest tooth on the drum 14. When the actuating lever of the machine is operated and the drum 14 is caused to be rotated, this tooth is brought into mesh with the pinion 22 and moves it and its shaft 11 one step, which step is of such a length that when the motion of the shaft 18 is, through the gearing 73, communicated to the numeral wheel 70, the digit "1" on that wheel is moved to proper position with respect to the other mechanism of the machine in the same manner as though, in the Rechnitzer patented machine, its slidable button had been moved along its slot to a position opposite the figure "1" and the parts had been properly actuated. Assuming that the calculation desired is, then performed upon the machine and the operator wishes to restore the keys to their initial positions, the handle 67 is then rotated to cause the shaft 66 and countershafts 63, 63, to revolve. This movement actuates the restoring bar 60 in a rearward direction, or to the right, when the parts are arranged as shown in Fig. 4 and as the bar comes into contact with the lower projecting member 30 of the carrier 21 (and with all the other carriers and pinions of the same denominational series which have been similarly moved into positions in contact with the keys of said series which have been depressed) it moves this pinion and its carrier 25 back to their original positions charging the spring 26 with sufficient energy again to retract the carrier, when desired, and seating the lug 41 of the latch 40 against the carrier 25 under the influence of the spring 42. If

one of the other keys, in the same series, had been depressed, for instance, the one displaying the digit "9" and which is at the other end of the series from that carrying the 5 digit "1" then the carrier 25 would slide along its rod and through all of the passage ways 57 of the keys which had not been depressed. During such movement the fingers 32 pass beneath the toes 56 of all of the key stems until they reach the toes of the foot of the key "9" which had been depressed, when, of course, the fingers would be above such toes. The carrier thus moves the slideable pinion 22 to a position under the key "9" and this pinion would then be opposite the shortest one 15 of the teeth 17 on the drum 14. When the operating lever of the machine is moved and the drum 14 rotated, the teeth of the pinion are brought into mesh in turn with every 20 tooth on the drum, namely, nine; and would thus cause the numeral "9" to be set up on the numeral wheel 70 at the proper position. The slideable pinion in such case is of course restored to its initial position by the actuation 25 of the handle 67 as before.

It will be noted that after one key of any denominational series has been depressed and the pinion carrier has engaged therewith, the depression of any other key in the same 30 denominational series has no effect on the digit so set, unless and until the parts are all restored to their initial positions.

What I claim as new is:—

1. In a calculating machine of the class 35 described, the combination with depressible keys, numeral wheels, a drum, mutilated gears thereon, and a shaft for actuating the numeral wheels, of means for gearing the drum with said shaft, normally held inoperative, and means actuated by depressing the 40 keys for releasing and permitting said gearing means to operate.

2. In a calculating machine of the class 45 described, the combination with numeral wheels, a shaft for actuating them, a drum, and a series of mutilated gears thereon, of a pinion on the shaft, means for bringing it into mesh with the mutilated gears, normally held inoperative, and manual means for releasing 50 and permitting the gearing means to operate.

3. In a calculating machine, the combination with a row of depressible keys numbered from 1 to 9 and a drum provided with mutilated gears, of a shaft between the drum and the keys, a slideable pinion on said shaft, and a connection between the keys and the pinion whereby the latter may be moved into line 55 with the mutilated gears by depressing the 60 keys.

4. In a calculating machine, comprising depressible keys, numeral wheels and drums each having mutilated gears, the combination therewith of a shaft for actuating the 65 numeral wheels, slideable pinions adapted to

actuate said shaft means for shifting said pinions into line with said mutilated gears and means actuated by depressing by the keys, for permitting said shifting means to operate.

5. In a calculating machine, the combination 70 with a row of depressible keys numbered from 1 to 9 and a drum provided with mutilated gears, of a shaft between the drum and the keys, a slideable pinion on said shaft, and a connection between the keys and the pinion 75 whereby the latter may be moved into line with a predetermined tooth on the mutilated gear upon the depression of the proper key.

6. In a calculating machine, the combination 80 with a row of depressible keys numbered from 1 to 9 and a drum provided with mutilated gears having a series of teeth of progressively increasing length, of a shaft between the drum and the keys, a slideable pinion on said shaft and a connection between 85 the keys and the pinion, whereby the latter may be moved into line with a predetermined tooth on the mutilated gear upon the depression of the proper key.

7. In a calculating machine of the class 90 described, the combination with depressible keys arranged in denominational series, numeral wheels, a drum, and a shaft for actuating the numeral wheels, of a slideable pinion on the shaft and, means actuated upon the 95 depression of the keys for moving the pinion into coöperative position with the drum, said means comprising a latch bar common to the series of keys connecting the key stems and the slideable pinion.

8. In a calculating machine of the character 100 described, the combination with depressible keys, numeral wheels, a drum, and a shaft for actuating the numeral wheels, of mutilated gears on the drums spaced apart, a 105 slideable pinion on the shaft normally out of coöperative position opposite the spaces between the mutilated gears, and means for sliding the pinion into line with the proper tooth of the mutilated gears where certain 110 key is depressed.

9. In a calculating machine of the character 115 described, the combination with depressible keys, numeral wheels, a drum, and a shaft for actuating the numeral wheels, of mutilated gears on the drum, a slideable pinion on the shaft normally out of line with the mutilated gears, and automatically operating means for shifting the pinion into line with the mutilated gears brought into action 120 upon the depression of the keys.

10. In a calculating machine, of the class 125 described, comprising keys, numeral wheels, a drum provided with mutilated gears, a shaft for actuating the numeral wheels and a slideable pinion on the shaft adapted when in proper position to mesh with the gears on the drum, means for moving the slideable pinion to proper coöperative position comprising a carrier for the pinion, a latch adapted to hold 130

it at rest, and means for moving the carrier to a predetermined distance upon the release of the latch.

11. In a calculating machine, comprising 5 numeral wheels and depressible keys arranged in series, and a slideable pinion adapted through intermediate mechanism to actuate said numeral wheels, means for moving the pinions to proper position to engage with 10 said mechanism, comprising a carrier for the pinion, a spring under tension secured thereto, a latch holding the carrier stationary, means for releasing the latch through the depression of any of the keys and a stop for the 15 carrier secured to the key depressed.

12. In a calculating machine of the class described the combination with depressible keys, numeral wheels, a drum and a shaft for actuating the numeral wheels, of means for 20 gearing the drum with said shaft, means for causing the gearing means to operate upon the depression of the keys, and other means for restoring the gearing means to their initial positions.

25 13. In a calculating machine of the class described the combination with a shaft for actuating the numeral wheels and a drum having a series of mutilated gears, of a pinion, means for normally holding it out of 30 mesh with said gears, gearing means for bringing said pinion into mesh with the mutilated gears, manually operable means for releasing the gearing means, and means for restoring the pinion to its initial position.

35 14. In a calculating machine of the class described, the combination with a shaft for actuating the numeral wheels, and a drum having a series of mutilated gears, of a pinion, means for normally holding it out of 40 mesh with said gears, gearing means for bringing said pinion into mesh with the mutilated gears, manually operable means for releasing said gearing means, and means for restoring the pinion to its initial position, 45 comprising a restoring bar adapted to be manually operated.

15. In a calculating machine, comprising keys, numeral wheels and drums each having mutilated gears, the combination therewith 50 of a shaft for actuating the numeral wheels, slideable pinions adapted to actuate said shaft, means actuated upon the depression of the keys for shifting said pinions into line with said mutilated gears, and means for 55 restoring the pinions to their initial position, comprising a manually operated bar.

16. In a calculating machine, comprising numeral wheels, and depressible keys arranged in series and a slideable pinion adapted 60 through intermediate mechanism to actuate said numeral wheels, means for moving the pinions to proper position to engage with said mechanism, comprising a carrier for the pinion, a spring under tension acting thereon, a

latch holding the carrier stationary, a bar 65 extending along the series of keys and adapted to release said latch and a stop secured to each key and adapted to be interposed in the path of the carrier when said key is depressed.

70 17. In a calculating machine, comprising numeral wheels and keys arranged in series and a slideable pinion, adapted through intermediate mechanism, to actuate the said numeral wheels, means for moving the pinions 75 to proper position to engage with said mechanism and means for restoring the pinion to its initial position after such engagement.

18. In a calculating machine, comprising 80 numeral wheels and depressible keys arranged in series and a slideable pinion adapted through intermediate mechanism to actuate said numeral wheels, means for moving the pinion to proper position to engage with said mechanism, comprising a carrier for the 85 pinion, a spring under tension secured thereto, a latch holding the carrier stationary, means for releasing the latch through the depression of any of the keys, a stop for the carrier secured to the key depressed and 90 means for restoring all of the parts to their initial position after such engagement.

19. In a calculating machine, comprising 95 numeral wheels and keys arranged in series and a slideable pinion adapted through intermediate mechanism to actuate said numeral wheels, means for moving the pinion to proper position to engage with said mechanism and means for restoring the pinion to 100 its initial position after such engagement and means for automatically replacing the latch in its initial position.

20. In a calculating machine comprising 105 numeral wheels and depressible keys arranged in series, and a slideable pinion adapted, through intermediate mechanism, to actuate said numeral wheels, means for moving the pinion to proper position to engage with said mechanism, comprising a carrier for the pinion, a spring under tension secured thereto, a latch holding the carrier stationary, means for releasing the latch through the depression of any of the keys and a stop for the carrier secured to the key depressed and holding it in said position during said 110 engagement.

21. In a calculating machine, comprising 115 numeral wheels and depressible keys arranged in series, and a slideable pinion adapted, through intermediate mechanism, to actuate said numeral wheels, means for moving the pinion to proper position to engage with said mechanism, comprising a carrier for the 120 pinion, a spring under tension secured thereto, a latch holding the carrier stationary, means for releasing the latch through the depression of any of the keys and a stop for the carrier secured to the key depressed and 125

holding it in said position during said engagement and restoring it to its initial position after such engagement.

22. In a calculating machine, comprising 5 numeral wheels and depressible keys arranged in series and a slidable pinion adapted through intermediate mechanism to actuate said numeral wheels, means for moving the pinion to proper position to engage with 10 said mechanism, comprising a carrier for the pinion, a passage in each key through which the carrier may pass, a latch holding the carrier stationary, means for moving the carrier and a stop on the key to determine the 15 position of the carrier when a key is depressed.

23. In a calculating machine, the combination with a depressible numeral key and a pinion carrier, of toes on the key adapted to 20 engage with the carrier to keep the key depressed.

pressed while the carrier is in engagement with the key.

24. In a calculating machine the combination of numeral wheels and depressible keys arranged in series and a slidable pinion 25 adapted through intermediate mechanism to actuate said numeral wheels when brought into engagement with any one key in the series which has been depressed, and means adapted to prevent any change in the digit 30 corresponding to the depressed key, by the subsequent depression of any other key of the same series.

In testimony whereof I affix my signature in presence of two witnesses.

CARL M. BERNEGAU.
